W. R. BAWDEN.

PATENTED OCT. 17, 1905.

CLINOMETER.

APPLICATION FILED DEO. 16, 1903.

UNITED STATES PATENT OFFICE.

WILLIAM REYNOLDS BAWDEN, OF KALGOORLIE, WESTERN AUSTRALIA,
AUSTRALIA.

CLINOMETER.

No. 802,071.

Specification of Letters Patent.

Patented Oct. 17, 1905.

Application filed December 15, 1903. Serial No. 185,232.

To all whom it may concern:

Be it known that I, WILLIAM REYNOLDS BAWDEN, a citizen of the Commonwealth of Australia, residing at Kalgoorlie, in the State of 5 Western Australia, Australia, have invented certain new and useful Improvements in Clinometers, of which the following is a specification.

The object of my improved clinometer is to 10 provide an instrument which will easily and accurately record the position and angle of bore-holes whether vertical or horizontal and at any point of locality in their line of travel.

As is well known in mining operations, the 15 diamond drill has a tendency to deviate from its desired or assumed line of travel by reason of pursuing the line of least resistance or other causes and which errors and consequent loss are the greater in hard and refractory coun- 20 try.

This clinometer has been principally de- 25 signed to record such errors, so that the travel of a diamond drill and consequent position of the bore may from time to time be checked and charted in order to ascertain the position 30 of the lode or other desired object as quickly and as cheaply as possible.

In this instrument the clinometer-case and the compass-box are provided with trans- 35 parent plates or windows which are placed in a parallel position to the planes of action of their respective operative parts, so making provision for observations to be taken at right angles to the point that is desired to be read, and thus effectively overcoming any errors 45 that would be produced by refraction arising by the instrument being inclosed within glass tubes or curved surfaces.

A further advantage consists that when the 40 clinometer is used for surveying a vertical or inclined bore-hole and upon the gelatin becoming firmly set the instrument may be placed in a horizontal position, thus giving a clear view of the magnetic needle, and, again, if 45 found necessary, the compass-box may be re- 50 moved from its gimbal and placed on the reading-protractor, with the object of bringing the needle as nearly as possible to the sighting-line.

55 The construction and arrangement of the clinometer will now be explained by the aid of the attached drawings and which illustrate same.

In the drawings, Figure 1 is a sectional ele-

vation of the instrument in its horizontal po- 55 sition and as placed within its outer protector-tube. Fig. 2 is a plan view of the actual in- strument and casing and as removed out of and from its bearings. Fig. 3 is a similar view to Fig. 2, but showing the instrument 60 as in the vertical position. Figs. 4 and 5 and 6 are transverse sectional views, respectively, on lines 1 2 and 3 4 and 5 6 of Fig. 1.

The carrying-frame or cradle, as a , is made open-spaced, as shown, and is secured by the 65 set-pins a' to the caps or ends a'' , which latter are formed with the solid portions a^3 in order to act as counterbalances to the instrument and cause it to assume and maintain a true hor- 70 izontal position. These ends a'' are formed with the trunnions a^4 , which pivot and carry the cradle and its contained instrument as a whole, and on one of these ends a'' is provided a re- 75 cess a^5 for a purpose hereinafter described. In this cradle is placed the central divisional wall a^6 and which is also formed with a solid por- 80 tion, as a^7 , in order to act as a further coun- terbalance.

The magnetic needle b and its pivot b' are in- 85 closed in its box b^2 , the outside surface of which is part of a sphere. This box is arranged with its gimbal or universal movement and trun- nioned at b^3 to the side of the cradle a . This box is solid-bottomed, and as the axis of its trunnions is always horizontal such bottom 90 will maintain the pivot b' of the magnetic nee- 95 dle in the true vertical position. The top of this box is adapted to be hermetically sealed, for which purpose it is provided with the screw-cap b^4 and with the plate b^5 , of mica, 90 glass, or of other approved transparent sub- 100 stance. The box is filled with its gelatin by means of the small opening b^6 and which is made secure by the flush-headed screw-cap b^7 . When in use, this box b^2 is filled with gelatin, 105 and upon the cooling of same it will concur- 110 rently act and fix the needle b in the position it occupies at such moment of time. In order that the trunnions b^3 of the compass-box may be held in position, they are provided with metal plates, as c , formed with bayonet- 115 catches c' , and these plates are secured by set- 120 pins c^2 to the cradle and as shown particularly in Fig. 3 of the drawings.

For the purpose of reading the vertical and horizontal dips or inclines of the bore-hole the instrument is provided with two pendulums and which are hereinafter referred to as the

"vertical" pendulum d and the "horizontal" pendulum d' . These pendulums are respectively pivoted, as at d^2 and d^3 , on opposite sides of a central and protractor plate d^4 , 5 which is interposed and held in suitable position in the pendulum-case. This plate d^4 is engraved or marked with the graduated arcs for use in conjunction with their own pendulum, that as d^5 for the horizontal pendulum being marked, preferably, for registering up to eighty degrees from the horizontal and that as d^6 for the vertical pendulum preferably for registering not greater than twenty degrees from the vertical. The pendulum-case, as e , 10 is removable and is held in position by the short clips e' and the long clip e^2 , which are attached to the pendulum-case and which engage the opposite edges of the cradle, as shown in Fig. 3. In this pendulum-case are interposed the windows e^3 , of glass or other transparent substance, and which windows are placed parallel to the protractor-plate d^4 , so as to avoid all errors arising from refraction. The pendulum-case e is provided at one end 15 with a neck e^4 , having an opening e^5 communicating with the interior of the case, through which the medium for setting the pendulums may be poured. This neck is covered by a cap e^6 , which is adapted to fit into 20 the recess α hereinbefore described.

The casings of the compass-box and pendulums are contained in an outer primary tube, as f , into the ends of which are interscrewed the caps or plugs, as f' . These caps are formed 25 with bearings for holding the trunnions a^4 of the instrument, as above mentioned. These caps are provided with the rubber buffers g , which act as antivibration agents in connection with the companion instruments which 30 may be in use at the same time. These caps f' are further provided with the vulcanite or leather rings g' in order to maintain the instrument in a central position within its outer protector-tube, as g^2 , and which latter tube 35 may be of any length and is common to and may contain any number of instruments.

The method for the use of the instrument is as follows: The pendulum-case e and compass-box b^2 are both filled with warm gelatin 40 or other similar transparent liquid and which acts as the medium for setting the pendulums d and d' and the magnetic needle b . The instrument is then placed within its primary case f , and for the better maintenance of the gelatin in a liquid form, if found likely to congeal owing to its small bulk, hot water or hot gelatin may be poured into the space inclosed 45 by the primary case f , causing the instruments to be held in a warm bath, and such water or gelatin would be removed prior to the reading of the result. The outer protector-tube g^2 , containing the instruments, is lowered or placed in that locality of the bore-hole which is to be charted. The instrument there 50 remains until such time as the recording gela-

tin has set hard, and thereby setting the needle b and the pendulums d and d' in the positions which they occupy at such moment of congealment. In the use of the instrument due care should be taken so that the gelatin 55 or other medium, owing to variations of temperature in the bore-hole, does not respectively congeal or liquefy prior to or subsequent to the time of the taking of the record. When the instrument is withdrawn from the bore-hole, the readings of the pendulums and compass may be made with greater or more precise accuracy by removing and placing each separately on a reading-protractor made 60 specially for such purpose.

What I claim as my invention, and desire to secure by Letters Patent, is—

1. In a clinometer, a protractor-plate provided with a plurality of arcs thereon, a plurality of pendulums pivoted to the plate, a casing adapted to contain the plate, means for removable attachment of the plate to the casing, and means to permit a view of the plate within the casing.

2. In a clinometer, a cradle, a casing adapted to receive the cradle, comprising a hollow member with caps thereon, and means for maintaining the cradle within the casing.

3. In a clinometer, a cradle, a casing adapted to receive the cradle, comprising a hollow member, screw-caps thereon and provided with openings in the screw-caps, and pivots on the cradle journaled in said openings.

4. In a clinometer, a cradle, a casing adapted to receive the cradle, means for maintaining the cradle in the casing, means in the cradle for indicating its direction, and means in the cradle for indicating its declination from a vertical and horizontal plane.

5. In a clinometer, a cradle, a casing adapted to receive the cradle, means for maintaining the cradle in the casing, means within the cradle for indicating and recording its direction and declination from a horizontal and vertical plane.

6. In a clinometer, a cradle, a casing adapted to receive the cradle, means for maintaining the cradle in the casing, and means for preventing vibration of the casing.

7. In a clinometer, a cradle, a casing adapted to receive the cradle, means for maintaining the cradle in the casing, and resilient members to prevent vibration of the casing.

8. In a clinometer, a cradle, a casing adapted to receive the cradle, means for maintaining the cradle in the casing, and rubber members secured to both ends of the casing.

9. In a clinometer, a tubular member, a casing within the tubular member, means for maintaining the casing in the center of said tubular member, a cradle within the casing, and means within the cradle for indicating its direction, and declination from a vertical and horizontal plane.

10. In a clinometer, a tubular member, a cas-

ing within the tubular member, annular members disposed between the tubular member and the casing, a cradle within the casing, and means within the casing for indicating its direction and declination from a vertical and horizontal plane.

11. In a clinometer, a tubular member, a casing within the tubular member, means for maintaining the casing in the center of the tubular member, a cradle within the casing, means for preventing vibration of the casing and cradle, and means within the cradle for indicating its direction and declination from vertical and horizontal planes.

12. In a clinometer, a tubular member, a casing within the tubular member, means for maintaining the casing in the center of the tubular member, a cradle within the casing, means for preventing vibration of the casing and cradle, and means within the cradle for indicating its direction and declination from vertical and horizontal planes.

13. In a clinometer, a tubular member, a casing within the tubular member, means for maintaining the casing in the center of the tubular member, a cradle within the casing, means within the casing for indicating its direction, comprising a removable, pivoted box provided with an opening therein, a compass disposed in said box, a closure for the opening, and means for indicating the declination of the cradle from vertical and horizontal planes.

14. In a clinometer, a tubular member, a casing within the tubular member, means for maintaining the casing in the center of the tubular member, a cradle within the casing, means within the cradle for indicating its direction, comprising a removable, pivoted box provided with an opening therein having a

screw-cap thereon and a sheet of transparent material disposed thereover, a compass disposed in said box, and a closure for the opening, and means for indicating the declination of the cradle from vertical and horizontal planes.

15. In a clinometer, a tubular member, a casing within the tubular member, means for maintaining the casing in the center of the tubular member, a cradle within the casing, means within the cradle for indicating and recording the direction of the cradle, comprising a removable, pivoted box provided with an opening therein, a compass disposed in said box, a closure for the opening, and a body of material to record the position of the compass at a predetermined time, and means for indicating the declination of the cradle from vertical and horizontal planes.

16. In a clinometer, a tubular member, a casing within the tubular member, annular members disposed intermediate of the casing and said member, means within the cradle for indicating and recording its direction and declination from horizontal and vertical planes, comprising a compass, disposed in a removable, pivoted box having a transparent cover thereover and an opening in the bottom thereof, with a closure for the opening, a plate provided with a plurality of graduated arcs of circles, a plurality of pendulums pivoted to the plate and registering in said arcs, and a body of gelatinous material disposed in said cradle.

In witness whereof I have hereunto set my hand in the presence of two witnesses.
